his ATTORNEY

UNITED STATES PATENT OFFICE

BENJAMIN A. LEVITT, OF NEWARK, NEW JERSEY

POWDER PUFF

Application filed February 1, 1930. Serial No. 425,289.

My invention relates to powder puffs and refers particularly to devices of this character of such construction that the operative face of the puff is protected.

5 Powder puffs are of two general characters, those which are enclosed in powder containers and those which are separate therefrom.

Powder puffs of the latter character are usually carried in hand bags, or similar receptacles, and hence the face of the puff is liable to become contaminated and unhygienic.

10 The puff of my invention is designed to overcome this objectionable feature, while at the same time being easy of construction and 15 presenting a pleasing appearance.

The device of my invention is composed of but two pieces, so sewed together that they produce a puff having a folding line arranged to give it an inclination to become 20 folded with the operative faces abutting; one modification of my device having a pocket whereby the puff may be retained in such folded position.

The device of my invention, therefore, presents both economy of production and efficiency of usefulness coupled with hygienic properties.

25 The novelty and advantages of my device will be evident upon a consideration of my specification and its accompanying drawings.

In the modified forms of the device of my invention shown in the accompanying drawings similar parts are indicated by similar numerals.

30 Figure 1 is a plan view of the front member of one form of my device.

Figure 2 is a plan view of the back member of one form of my device.

Figure 3 is a plan view of my device when 40 the front member and the back member are sewed together.

Figure 4 is a section through the line 4—4 of Figure 3.

Figure 5 is a section through the line 5—5 of Figure 9.

Figure 6 is a perspective view of my device in folded position.

Figure 7 is a section through the line 7—7 of Figure 6.

50 Figure 8 is a perspective view of a modified

form of my device in open position for use.

Figure 9 is a perspective view of my device in open position, adapted for use.

The particular form of the device of my invention shown in Figures 1 to 7, inclusive, 55 comprises a front member 10 rounded at one end and having a slit 11 therein and a back member 12, rounded at one end to conform to the rounded end of the front member 10. I prefer to employ a material for the front member, the face of which is soft and fluffy for reasons described later.

In combining the two members, I fold the member 12 along the line A—A, thus forming a flap 13. I then place the front member 10, soft side in, upon the back member 12 and sew them together around the edges by the stitches 14. I then reverse the device by passing the back member 12 through the slit 11, the device then being as shown in Figure 5 with the soft face of the front member 10 outside. It will be noted that the flap 13 of the back member 12 thus forms a pocket. I then place sheets of padding 15, 15 between the front and back members, and sew the device along the line B—B, thus closing the slit 11. It will thus be seen that my device, and especially the rounded portion of the front member 10, may be used as a powder puff.

When it is desired to close the device prior to placing it within a hand-bag or other receptacle, the rounded portion of the front 10 is bent over at the line of the slit 11 and inserted in the pocket formed by the flap 13 as shown in Figures 6 and 7. The face of the front member 10 is thus folded upon itself and any powder adhering thereto will not come in contact with other articles in the receptacle.

The modified form of my device shown in Figure 8 is similar to that previously described except that it has no flap 13.

It will thus be seen that my device presents a powder puff made of two pieces of material, so arranged that the operative sides 95 may be folded upon each other, in which the edges of the two pieces at the lines of sewing are concealed and in which the slit, or opening, necessary for the formation of the device is also concealed.

I do not limit myself to the particular size, shape, number, material or arrangement of parts as shown and described as these are given simply as a means for clearly describing the device of my invention.

What I claim is:—

1. In a powder puff, in combination, a back member, a front member, stitching connecting the entire edges of said two members with the raw edges of said members concealed within the device, and a transverse line of stitches forming a turned over seam approximately mid-way of the end extremities of said members.
2. In a powder puff, in combination, a back member, a front member having a transverse slit capable of allowing the passage of back member therethrough, stitching connecting the entire edges of said members with the raw edges of said members concealed within the device and a transverse line of stitches connecting the said members and concealing said slit.
3. In a powder puff, in combination, a back member, a front member, stitching connecting the entire edges of said two members with the raw edges of said members concealed within the device, a pocket formed by said back member above the exposed face of said front member and capable of receiving a portion of the device when it is in folded position, and a transverse line of stitches forming a turned over seam approximately midway of the end extremities of said members.
4. In a powder puff, in combination, a back member, a front member having a transverse slit capable of allowing the passage of back member therethrough, stitching connecting the entire edges of said two members with the raw edges of said members concealed within the device, a pocket formed by said back member above the exposed face of said front member and capable of receiving a portion of the device when it is in folded position, and a transverse line of stitches connecting the said members and concealing said slit.

Signed at New York city, in the county of New York and State of New York, this 28th

day of January, 1930.

BENJAMIN A. LEVITT.
